UNITED STATES PATENT OFFICE.

JOHN B. LITCHMAN, OF MARBLEHEAD, MASSACHUSETTS.

SHOE-MAKER'S JACK.

SPECIFICATION forming part of Letters Patent No. 453,401, dated June 2, 1891.

Application filed March 20, 1889. Serial No. 304,018. (No model.)

To all whom it may concern:

Be it known that I, JOHN B. LITCHMAN, of Marblehead, in the county of Essex and State of Massachusetts, a citizen of the United States, have invented a new and useful Improvement in Shoe-Makers' Jacks, of which the following is a full, clear, and exact description, reference being had to the accompanying drawings, forming a part of this specification, in explaining its nature.

The invention is in some particulars an improvement upon that described in my patent, No. 331,414, dated December 1, 1885; and it relates especially to the manner of attaching the last to the jack-post, to the construction of the last, whereby this is possible, and to certain other details of construction, all of which will hereinafter be described.

Referring to the drawings, Figure 1 represents, partly in side elevation and partly in section, my improved invention. Fig. 2 is an end view thereof. Fig. 3 is a view in front elevation representing the jack as turned to a horizontal position. Figs. 4 and 5 are views of the last. Figs. 6, 7, and 8 are detail views, to which reference is hereinafter made.

In the drawings, A is a standard or post adapted to be fastened to a bench or other suitable support.

B is a hanger movable vertically upon the arm B', and which supports the jack C, and is attached to the standard or post and adjustable or movable thereon in the manner described in my said patent.

The jack C comprises the post c, preferably made of metal, having the shoulder c', which rests upon the upper arm b of the bracket B, and the spindle c², which passes through the holes b' in the arm b of the bracket, a hole b² in the arm b³ of the bracket, and is adapted to rest upon or come in contact with the bed or upper surface b⁴ of a stationary bracket b⁵, belted or otherwise attached to the edge of the standard or post A. The spindle c² serves to secure the jack-post C to the bracket to permit the post to be rotated upon a vertical axis in relation to the bracket, and also provides a means of firmly supporting the jack when in a vertical position by resting or bearing upon the bed or surface of the stationary bracket b⁵. To lock the jack-post to its sup-

porting-bracket B in any required position, I employ a set-screw b⁶, which is carried by the arm b³ of the bracket B and is adapted to be screwed against the spindle c². The main part of the jack-post C is preferably made hollow or provided with an interior cavity c³, and there is a narrow or long opening c⁴ through the front of the jack-post to this cavity, and in this opening c⁴ is secured, by means of a pivot c⁵, a latch c⁶. This latch has the thumb-piece or arm c⁷, by which it is moved, and has the latch c⁸ at its upper end, which preferably is formed substantially as represented in Fig. 1—that is, with the rounded corner c⁹ and the inclined under edge c¹⁰. A spring c¹¹ serves to keep the inner end of the latch always in operative position to engage the catch of the last.

D is the last. It may be of wood or of metal. It preferably is of metal. It has extending from its top surface a wedge-spindle d. This spindle preferably has the rounded front lower corner d' and is inclined or tapered from the point or line d² to the surface of the last, (see Fig. 1,) and is also wedge-shaped in cross-section, being wider at the front than at the rear, and it is of a size to enter the upper end of the cavity c³ of the jack-post. This cavity has practically the shape of the spindle—that is, it has the tapered or inclined surface d³, corresponding to the tapered or inclined section d² of the spindle, and is otherwise of the shape of the spindle. The spindle also has a catch or latching-recess d⁴ to receive the latch c⁸. The upper edge of this recess preferably is rounded, and the lower edge preferably is of such shape that the inward movement of the latch c⁸ causes its inclined under edge c¹⁰ to bear against the under surface of the latching-recess and draw the last downward firmly upon the upper surface d⁵ of the jack-post. This construction provides for a wearing end for both the last-spindle and the latching device. It will be observed that the surface d⁶ of the last about the spindle is flat and of a size to provide a firm rest upon the top of the jack-post.

In Fig. 5 I have represented the spindle d² as secured to a wooden last, and in this case it is of course of metal, and is provided with the plate e, by which it is secured to the

wooden last by means of screws or other fastenings, and the surface e' of which forms the part of the last which comes in contact with the top of the jack-post.

5 Having thus fully described my invention, I claim and desire to secure by Letters Patent of the United States—

1. The improved shoe-maker's jack having the adjustable hanger B, the jack C, having 10 a latch c^6 of the character specified, and an end opening c^4 , with a last having the spindle and latching-recess d^4 , substantially as described.

2. The improved shoe-maker's jack comprising a post or support A, the adjustable bracket B, pivoted to the upper end of the post and having the arms b^3 , the jack-post C, having the spindle c^2 extending through holes in said arms to rest upon the bed b^4 , secured 20 to said post A and the said bed a^4 , as and for the purposes described.

3. The combination of the jack-post C, hav-

ing a slot upon one side, in which is a latch c^6 , the said latch having the end c^8 , provided with the inclined edge c^{10} , the operating-arm c^7 , the spring c^{11} , and the last-spindle having a latch-recess d^4 , with an inclined or tapering lower surface, against which the inclined surface of the latch comes in contact, substantially as described.

4. The combination of a jack-post having a flat upper surface d^5 , an opening of the character specified extending from said surface downwardly to a cross-opening, a latch contained in said cross-opening and arranged 30 to shut into the said first-named recess or opening, a last having a spindle of the character specified to fit the said first-named opening, and a latching-recess to receive the latch, as and for the purposes described.

JOHN B. LITCHMAN.
